UNITED STATES PATENT OFFICE.

GUSTAV J. GRUENDLER, OF CLAYTON, MISSOURI.

EXTENSIBLE LEG.

Application filed October 12, 1921. Serial No. 507,397.

My invention relates to extensible legs and more particularly to extensible legs having a shank adapted to slidably fit within a socket which is formed in the upper and attaching 5 portion of the leg. My invention relates further to an extensible leg as described above and which is adapted to support a weight and to be pivotally mounted on the end of a drawer or other pull-out receptacle 10 to support the end of the receptacle when it is pulled out from the frame in which it slides.

Heretofore in extensible legs there has been no convenient way of registering the 15 holding means in the walls of the socket in the upper portion of the leg with that part of the shank adapted to engage the holding means. The objects of my invention are to provide an extensible leg in which the holding 20 means in the walls of a socket in the upper portion of the leg may be quickly and easily brought into engagement with that part of the shank adapted to receive the holding means; to provide an extensible leg 25 having a socket in the upper portion thereof and a shank adapted to slidably fit in said socket, the socket and the shank being arranged so that the shank cannot turn in the socket and the holding means in the wall of 30 the socket will always be in vertical register with that part of the shank adapted to receive the holding means; to provide an extensible leg having a shank with a part thereof arranged with a plurality of inwardly 35 extending holes formed so that they may be quickly and easily brought into horizontal register with the holding means in the walls of the socket in which the shank slidably fits; and to provide an extensible 40 leg which is adapted to be pivotally mounted upon a pull-out receptacle so that the leg when not in use may be swung out of engagement with the surface on which it rests when said receptacle is pulled out.

My invention is fully shown in the accompanying drawings wherein similar letters are used to designate similar parts. Fig. 1 is a view of an extensible leg embodying my invention showing in elevation the arrangement of the parts; Fig. 2 is a view of the 50 upper portion of the leg; Fig. 3 is a view of

the lower portion adapted to slidably fit in the socket in the upper portion; Fig. 4 is a cross section along the line 4-4 in Fig. 1; Fig. 5 shows a detail of construction; Fig. 6 55 shows the extensible leg mounted on a drawer; Fig. 7 shows details of the leg as adapted to be mounted on the drawer.

Referring to the figures it is seen that the extensible leg comprises the upper portion A 60 having the socket B extending upwardly from the lower end thereof. The socket B is, preferably, square in cross section, but it may be of any non-circular shape. The lower portion of the extensible leg has the 65 shank C adapted to slidably fit the socket B, as shown in Fig. 4, and arranged on the lower end thereof the foot D, or any other suitable means whereby the leg will be prevented from injuring the surface upon which 70 it rests. A part of the shank C is arranged with a plurality of inwardly extending holes E, as shown in Figs. 1 and 4, which, as shown, preferably have their walls for a greater portion of their length arranged at 75 substantially right angles to the side of the shank and have the outer ends of their walls arranged with the bevels E'. As shown in the figures the holes E are spaced so that the bevel E' of one hole substantially meets 80 the bevels E' of the adjacent holes, for the purpose hereinafter described. The front wall of the socket B is provided with the block F and is arranged with a hole extending through said block and the wall of the 85 socket B, the hole being threaded to receive the substantially cylindrical bolt G. The upper end of the upper portion A is arranged with the shoulders H, as shown in Figs. 1 and 2, which have therein the oppositely disposed holes J. The extensible leg 90 may be mounted in any way, but in the figures it is shown as pivotally mounted on a drawer or other pull-out receptacle, and therefore the plate K having the projecting lug L is adapted to be fastened to the bottom of the drawer or other pull-out receptacle, as shown in Fig. 7, whereby a pin passing through the oppositely disposed holes J in the shoulders H and through the hole in the lug L will pivotally attach the extensible leg 95 to said pull-out receptacle. As it is usually 100

necessary to use two legs on each drawer or other pull-out receptacle the upper portion A is arranged with the perforations M and is adapted to receive one end of a connecting strip N, as shown in Figs. 6 and 7. The strip N is attached to each leg by bolts or other suitable means passing through the perforations M.

When the receptacle upon which the extensible leg is used is pushed into the frame upon which it is mounted, the two extensible legs are swung up underneath the receptacle, as shown in Fig. 7. The button O, or any other means suitable to the purpose, is provided to hold the legs and the strip N in place underneath the receptacle. When the legs are allowed to swing downwardly into engagement with the surface upon which the frame rests the upper sides of the shoulders H come in contact with the plate K, as clearly shown in Fig. 6, and the legs are prevented from swinging further outwardly from the frame holding the receptacle then to a right angle with the bottom thereof. When the legs are in the position last named, the shank C is moved in the socket B until the foot D is upon the floor or other surface upon which the frame rests, and the bolt G is turned in the threaded hole in the block F until it enters one of the holes E and thereby maintains the shank C in determined position in the socket B. Since the socket B and the shank C adapted to fit therein, are non-circular in cross section, the shank cannot rotate in the socket, and therefore the end of the bolt G will always be in vertical register with the holes E. The holes E are provided at their outer ends with the bevels E' so that it will be easy to bring the holes in the shank C horizontally in register with the bolt G, and since the bevels E' of adjacent holes substantially meet, as described above, when the bolt is screwed in it will strike the bevel E' of one of the holes and will move the shank until the hole registers with the bolt G so that the bolt G can be made to enter the hole. The inner end of the bolt G may also be beveled thereby aiding to bring the bolt and the holes E in register. When the extensible leg is adjusted to the proper length, the bolt G is turned through the block F far enough so that the side of the shank C opposite said bolt is forced into engagement with the oppositely disposed wall of the socket B, as shown in Fig. 4, and the shank is thereby rigidly held in the socket. Since the bolt G is substantially cylindrical and the walls of each of the holes E are for a greater portion of their length at substantially right angles to the side of the shank a substantial engagement will be had between the bolt and the walls of the hole and a comparatively great weight may be supported by the leg without breakage of any of the parts.

It is obvious that it is not my intention to limit my invention to an extensible leg having a socket and shank square in cross section, since it is clear that if the socket and shank are formed so that the shank is prevented from turning in the socket such a construction would come within the spirit of my invention. Furthermore, I do not intend to limit the use of my extensible leg for attachment to a drawer or other pull-out receptacle although the form of the leg shown in the drawings is primarily intended for use where the leg may be pivotally mounted.

What I claim as new and desire to secure by Letters Patent, is:

1. An extensible leg comprising an upper portion having a socket extending upwardly from the lower end thereof, a lower portion having a shank adapted to slidably fit in said socket, said shank being provided with a plurality of substantially circular holes, the walls of said holes having the outer edges thereof beveled, and means extending through the wall of said socket and adapted and arranged to enter any one of said holes whereby said lower portion may be maintained in adjusted position in said socket, said holes being spaced so that the beveled surface of one hole substantially meets the beveled surface of the adjacent hole whereby said means will be brought into register with one of said holes.

2. An extensible leg adapted to support a weight and comprising an upper portion having a socket extending upwardly from the lower end thereof, a lower portion having a shank adapted to slidably fit in said socket, said shank being provided with a plurality of holes in alignment, a cylindrical bolt threaded through the wall of said socket and adapted to enter any one of said holes, the walls of each of said holes for a greater portion of their length being at substantially right angles to the side of said shank and the outer ends of said walls being beveled whereby when the inner end of said bolt is moved in engagement with the beveled portion of the walls of one of said holes said shank will be moved to allow said bolt to enter said hole so as to cause the sides thereof to bear against the walls of said hole to carry said weight and hold said socket and said shank in adjusted relation.

3. An extensible leg comprising an upper portion having a socket which is non-circular in cross section extending inwardly from the lower end thereof, a lower portion having a shank shaped to conform to the cross section of said socket and adapted to slidably fit therein, said shank being provided with a plurality of substantially circular holes in alignment, a bolt threaded through the wall of said socket and adapted to enter one of said holes, the walls of each of said holes for a portion of their length being at sub-

stantially right angles to the side of said shank and the outer ends of said walls being beveled, said holes being spaced so that the beveled surface of one hole substantially ⁵ meets the beveled surface of the adjacent holes whereby when said bolt is turned inwardly through the wall of said socket it

will engage the beveled surface of one of said holes to move said shank to bring said hole into horizontal register with said bolt. ¹⁰

In witness whereof I have signed my name to this specification.

GUSTAV J. GRUENDLER.
